UNITED STATES PATENT OFFICE.

LEO BLUHM, OF NEW YORK, N. Y.

DESIGN FOR A WOVEN FABRIC OR SIMILAR ARTICLE.

Application filed March 17, 1926. Serial No. 16,961. Term of patent 3½ years.

To all whom it may concern:

Be it known that I, LEO BLUHM, a citizen of the United States of America, and a resident of the city of New York, borough of Manhattan, in the county and State of New York, have invented a new, original, and ornamental Design for a Woven Fabric or Similar Article, of which the following is a specification.

Reference is to be had to the accompanying drawing in which the figure is a plan view of a swatch of fabric showing my new design.

I claim—

The ornamental design for a woven fabric or similar article as shown.

LEO BLUHM.
